UNITED STATES PATENT OFFICE.

FREDERICK ERNST GOLDSMITH, OF MIDDLETOWN, OHIO, ASSIGNOR TO THE CERAMIC MACHINERY COMPANY, OF HAMILTON, OHIO.

KILN.

985,797.

Specification of Letters Patent.

Patented Mar. 7, 1911.

Application filed April 25, 1905. Serial No. 257,373.

To all whom it may concern:

Be it known that I, FREDERICK E. GOLDSMITH, a citizen of the United States, and a resident of Middletown, in the county of 5 Butler and State of Ohio, have invented certain new and useful Improvements in Kilns, of which the following is a complete specification.

The present invention relates to kilns.

10 This kiln is adapted for burning all earthenware, pottery, and other clayey objects, either in the mold, biscuit or in the coating or glazing of the biscuit. The kiln is not only adapted for the above described purposes, but its use is contemplated in any art 15 to which it may be found to be applicable.

The pottery kilns in use at the present time are almost universally constructed of cupola form, openings being made in the 20 side through which the saggers containing the earthenware are placed, and having the usual furnaces and accessories well known to the art. The labor involved in filling, firing, cooling and removing the products of 25 the kiln is a labor involving several days.

The present invention reduces the labor of days to a comparatively few hours.

The construction and operation of the kiln will be developed in the following description, the invention consisting in the combination of parts set forth in the accompanying 30 claim.

Figure 1 represents a transverse vertical section of a kiln to which my improvements 35 have been applied. Fig. 2 is a plan of the same upon a reduced scale. Fig. 3 is a side elevation of one of the trucks showing the pedestal broken away. Fig. 4 represents a 40 perspective detail of a portion of the floor of one of the trucks. Fig. 5 illustrates a method of closing the joints of portions of the sectional kiln.

In the drawings:—1 represents a kiln, which may be, for illustrative purposes, say 45 300 feet long. The kiln is open at both ends and is provided with a retort chamber 2 of the same length as the kiln and also open at both ends. This retort is provided preferably with a long slot 3, the length of the 50 kiln, projecting downwardly from the retort 2. Through this retort is passed a table or a series of tables 4 provided with pedestals, supported by upwardly projecting pedestals 6 supported upon trucks 7 running through 55 a truck chamber 8 at the bottom of the kiln.

The objects to be burned or baked are placed upon the tables 4 at one end of the kiln and the tables are fed therein, by power-driven means continuously and slowly through the kiln, emerging at the opposite end with the products completely burned.

Proceeding with the drawing:—9 represents rails upon which the trucks run.

10 are the wheels of the trucks preferably provided with flanged portions engaging the 65 rails and with other flanged portions permitting the truck to be run upon a flooring not provided with rails.

11 represents truck axles.

12 are springs for yieldingly supporting 70 the pedestal 6.

13 are the side walls of the kiln.

14 are the furnaces which may be fed by gas through pipes 15 or by coal upon grates 16.

75 Walls 17 are introduced between the furnace chambers, the truck chamber 8 and the slotted vertical opening 3. All the parts subject to direct action of the fire are made of fire clay, or the like.

19 are slabs of fire clay resting on the top of the furnaces 14 and provided with flue 80 passages 20 for conveying the products of combustion into the chamber 21 surrounding the retort 2. This chamber 21 is connected at intervals with stacks 22.

85 The kiln may be economically built by providing the sides of the chamber 21 with vertical and horizontal linings 23 upon which the slabs 19 may rest, and providing 90 fire clay bracket shaped moldings 23 resting in the side walls of the brick work. These brackets 24 are provided with seats for roofing-sections 25. I prefer to provide two of these sections of the same or similar shape 95 with a dead air space 26 between them, and key them at top by keystone block 27 of fire clay forming the apex of the kiln. The buck stays 28, braces 29 and side-beams 30 afford a convenient means of making the 100 kiln rigid and secure.

105 31 represents a means for moving the trucks and tables continuously through the kiln, the particular means being an endless chain having projections 32 thereon at intervals adapted to be brought into contact with corresponding projections 33 depending from the truck portion of the tables, a succeeding chain projection being brought in contact with each newly laden table bear- 110

ing the mold or object to be burned. After the respective trucks and the tables are discharged at the opposite ends of the kiln they become automatically detached from the power impelling mechanism, and thereafter may be handled in any manner which will result in their being eventually brought back to the feeding end of the kiln freshly supplied with new objects to be baked.

10 Instead of there being a series of tables and trucks the table may be an endless continuously moving platform, capable of course of being controlled, and an endless track may be used for the purpose. The kiln may be built in a straight line or it may be ring shaped or endless.

The slabs 19 and parts 23, 24, 25, 27 and the like may be of block form of any desirable size, produced by suitable molds, and arranged to break joints with one another. Likewise the retort 2 is preferably composed of sections of any suitable dimensions set side by side. Fig. 5 represents a means of jointing these sections by forming flanges or offsets upon their respective meeting edges and filling the same by insertions of fire clay 34 at the joints.

35 represents spuds which may be formed upon the top of the tables 4.

30 36 is an opening which may be formed in the retort 2 at intervals leading to the exterior air for the purpose of carrying off any undesirable fumes from the retort.

35 is a peep-hole tube leading from the exterior of the kiln to the interior of the retort above the table 4. These tubes may be placed at convenient places in the length of the kiln.

In the movement of the tables through the retort it is generally very desirable to gradually increase the temperature of the firing from the time a given table enters the kiln to some point midway of the length thereof, and also thereafter to gradually decrease the intensity of the firing until the table with the object to be fired eventually leaves the kiln. By a process similar to that above recited the most effective firings of pottery, earthenware, tile and the like are accomplished. The line 38 illustrates diagrammatically the gradual rise of the temperature of the kiln to a point 39 intermediate

of the length of the kiln and the gradual decrease of the temperature from that point to the discharge end of the kiln. One means of effecting this highly desired object consists in placing the outlet stacks 22 leading from the fires closer together where the heat is desired to be more intensive, and to accordingly increase the number or intensity of the fires. In such a plan the stacks 22 will be common to the different fires or batteries of fires and the products of combustion will be free to seek the respective stacks in either direction. Generally it will be desirable to form a head at each end of the kiln which will serve in breaking up any undue draft that might be generated in the kiln by abnormal atmospheric conditions.

My kiln contemplates the simultaneous movement of the tables, their introduction into the kiln, the firing, their exit and the removal of the earthenware therefrom in one continuous operation.

The kiln may be made movable and travel over a stationary table in the retort. In some instances it is desirable to do away with the retort walls 2, and perhaps the slabs 19, and carry the tables 4 in direct contact with the products of combustion in the heating chamber. In such case the tables may carry saggers, properly sealed, containing the objects to be fired. The table or floor 4 may run up on and be supported by the walls of the heating chamber, if desired.

I claim as my invention:—

The combination of side walls, brackets therein, fire-clay slabs resting on the brackets, a relatively long retort resting on the slabs, the slabs being separated centrally to provide a slot communicating with the retort, a truck chamber operating the retort and communicating with the slot, fire chambers beneath the slabs, fire-proof walls between the fire chambers and the slot and the truck chamber, a roof provided with insulating spaces and spaced away from the wall of the retort, and flues leading from the fire chambers to the space around the retort.

FREDERICK ERNST GOLDSMITH.
